CLAIM

I claim the ornamental design for the plungerless syringe, as shown and described.

DESCRIPTION

FIG. 1 is a front elevational view of a plungerless syringe showing my new design, the rear elevational view being a mirror image thereto;

FIG. 2 is a top plan view thereof;

FIG. 3 is a bottom plan view thereof; and

FIG. 4 is a right side elevational view thereof, the left side elevational view being a mirror image thereto

FIG. 5 is a front elevational view of a second embodiment of a plungerless syringe showing my new design, the rear elevational view being a mirror image thereto;

FIG. 6 is a top plan view thereof;

FIG. 7 is a bottom plan view thereof; and,

FIG. 8 is a right side elevational view thereof, the left side elevational view being a mirror image thereto.
